RESILIENT SNAP HOOK

Robert C. Legat, New Britain, Conn., assignor to
 The G. E. Prentice Mfg. Co., Kensington, Conn.,
 a corporation of Connecticut

Application May 11, 1948, Serial No. 26,259

1 Claim. (Cl. 24—237)

1

This invention relates to key cases, and has to do more particularly with the hooks whereby the keys are attached to such cases.

An object of the invention is to provide an improved key case hook made of sheet metal rather than wire, as is usual.

A further object of the invention is to provide a key case hook composed of sheet metal and which is sturdy in construction, economical to manufacture, and possessing certain advantages over the usual form of hook made of wire.

The advantages of the key case hook of this invention, as well as the novel features of construction thereof, will be apparent from the following description when read in connection with the accompanying drawings, in which Fig. 1 is an enlarged plan view of the blank from which the key hook is made; Fig. 2 is a rear elevational view on an enlarged scale of the completed key hook; Fig. 3 is a side elevational view of the key hook shown in Fig. 2; Fig. 4 is a front elevational view of the same; Fig. 5 is a horizontal sectional view taken along the line 5—5 of Fig. 3, and Fig. 6 is a side elevational view, partly in vertical section, of the key hook.

In the drawings, the reference numeral 10 designates generally the blank from which the key hook of this invention is made. The blank may be made from any desirable type of sheet metal, but is preferably made from a carbon steel or phosphorus bronze sheet approximately $\frac{3}{16}$ of an inch thick. The blank 10 is approximately $2\frac{1}{4}$ inches in length and has a shank portion 11 approximately $1\frac{1}{8}$ inches long and $\frac{3}{8}$ of an inch wide. The lower end of the shank portion 11, as viewed in Fig. 1 of the drawings, is tapered to provide a reduced end portion 12 about $\frac{1}{8}$ of an inch in length. At the upper end of the shank portion 11, is an enlarged portion 13 provided with convexly-shaped side edges, such portion 13 being approximately $\frac{1}{8}$ of an inch in length and having a maximum width of about $1\frac{1}{16}$ of an inch. The top of the blank 10 is provided with three projecting portions or lobes 14, 15 and 16, of substantially triangular form and having convexly-shaped side edges; the configuration of such lobes being such that they may be formed into the hollow ball-shaped head 17 shown in Figs. 2, 3 and 4 of the drawings.

In the formation of the key hook from the blank shown in Fig. 1 of the drawings, the ball-shaped head 17 by which the hook is pivotally supported on the holder of the key case, is formed from the three projecting portions 14, 15, 16 of such blank, as has been previously mentioned.

2

The enlarged portion 13 is folded longitudinally to provide two spaced, longitudinally disposed ears 18, 18. The shank portion 11 is then bent in the form of a tear drop-shaped loop so as to position the reduced portion 12 thereof between the spaced ears 18, 18; the reduced portion 12 being preferably curved outwardly, as shown more clearly in Fig. 6 of the drawings, so that its outer free end normally rests against the associated surface of portion 13 between the ears 18, 18.

It will be noted that the leg portion of the loop provided with the reduced end portion 12 is a spring member which maintains such reduced portion in the U-shaped cavity formed by the ears 18, 18 of the enlarged portion 13. One function of the ears 18, 18 is to maintain the reduced portion 12 in position with relation to the head end of the hook and the associated shank portion. Another function of the ears 18, 18 is to provide a guard against the possibility of the reduced end 12 catching on the material of the key case or the garments of the user. The ears 18, 18 also facilitate the insertion and removal of a key on the hook. Thus, if a key is to be inserted on the hook, the required opening between the reduced end 12 and such ears may be obtained either by inserting the finger nail under the end of member 12 and then moving it inwardly over the outer edge of such ears, or by inserting the finger nail between such members at the upper end of the loop and moving it outwardly over the outer edges of the ears 18, 18. In either case, as the finger nail is moved over the outer edges of ears 18, 18 the latter will exert a camming action to force the reduced end 12 outwardly a sufficient amount to enable a key to be inserted thereon. When a key is to be removed from the hook, it is only necessary to grasp the key and move it outwardly over the outer edges of ears 18, 18 which, because of their camming action, will cause the reduced end 12 to be moved outward sufficiently to release the key. When the key is in proper position on the hook, the ears 18, 18 will prevent it from unintentional disengagement therefrom. The ears 18, 18 also enhance the looks of the key hook, giving it a distinctive, attractive appearance. The hook is sturdy and may be readily manufactured in quantity at low cost.

While I have illustrated and described a preferred embodiment of the invention, it will be evident to those skilled in the art, that various changes and modifications may be made therein without departing from the spirit of the invention.

tion, or the scope of the appended claim. Thus, it will be obvious, that the reduced end 12 and ears 18, 18 may have any desired configuration which will enable them to cooperate in the manner explained and such reduced end may be constructed to be entirely within the confines of the ears 18, 18. In this latter connection, the hook will be opened by moving the finger nail or any other device outwardly toward the head of the hook in the manner previously explained.

I claim:

A key hook comprising a shank composed of an elongated strip of sheet metal bent intermediate its ends to provide two legs forming a closed loop, an attachment member connected to the upper end of the longer leg of said shank, the other end of said shank being of reduced width and connected to the body of the shank by a tapering portion thereof, the free end of said reduced shank portion having its inner surface resting against the inner surface of an intermediate portion of the longer leg of said shank positioned in spaced relation below said attachment member to form the closed end of the loop, the leg portions of such shank below the closed end of the loop extending downwardly in spaced, diverging relation, and a pair of projecting ears integrally connected to the side edges of the sheet metal material forming the longer leg of said shank and projecting in substantially parallel relation from the inner surface thereof to form with a portion of the latter a U-shaped housing, in which the inner surfaces of the side edges thereof are spaced apart a distance less than the width of such shank between such housing and the tapering portion thereof, said ears having convexly-shaped, cam-like outer edges whose highest points are located intermediate their

lengths and below the extremity of the other shank end and said ears being so located on the longer leg of said shank that the upper ends thereof are adjacent to and conceal the closed end of the loop, the reduced other end of said shank extending downwardly between said ears and emerging from between the latter at a point adjacently below the high points of the outer edges of such ears, such reduced shank end and the outer edges of said ears below such point of emergence being arranged in diverging relation to provide a space therebetween sufficient to enable a fingernail to be inserted therebetween and engage a point on the outer edges of said ears under such reduced shank end, whereby when the fingernail is moved upwardly over the outer edges of such ears towards the high points thereof, such reduced shank portion is cammed outwardly sufficiently to enable a key to be inserted on the hook.
